OPERATING MECHANISM

Einar Almdale, Detroit, Mich., assignor to The Midland Steel Products Company, Cleveland, Ohio, a corporation of Ohio

Application August 25, 1932, Serial No. 630,420

4 Claims. (Cl. 74—512)

This invention relates to new and useful improvements in control mechanisms and more particularly to mechanical control means for operating an instrumentality situated remotely therefrom.

An important object of the invention is to provide a portable control of the above character which can be readily moved to be disposed in various places as the exigencies of the case require and at the same time to provide the same convenience of operation as though the operator were to stand directly beside the instrumentality to be controlled.

Another important object of the invention is to provide a remote control device having parts which will always lie close to the floor to obviate the danger of workmen tripping over the same and being thrown and also to provide an arrangement requiring intentional actuation to cause its operation and one which cannot be accidentally operated by falling objects or by workmen tramping over the device.

A still further object of the invention is to provide an arrangement in which the lubricant employed in the operation of the device is precluded from leakage.

A still further object of the invention is to provide a comfortable treadle mechanism having its parts arranged to obviate frictional resistance as far as possible, and one in which the arrangement of parts will induce positive action of the device when an operator's foot is properly associated therewith to actuate the control device.

Other objects and advantages of the invention will become apparent during the course of the following description.

In the accompanying drawing forming a part of the description and wherein like numerals are employed to designate like parts throughout the several views.

Fig. 1 is a side elevation of the device showing it applied to an instrumentality to be controlled.

Fig. 2 is a top plan of the portable foot treadle with a portion of its closure removed.

Fig. 3 is a longitudinal vertical section of the same.

Fig. 4 is an enlarged sectional view illustrating the manner of connecting the flexible conduit to the base of the treadle.

While the control device has been illustrated in the present drawing in conjunction with a specific instrumentality to be controlled, it is to be understood that the invention is in no wise limited to use in conjunction with such instrumentality, but is of general application.

Referring now more particularly to the drawing wherein for the purposes of exemplification is shown one application of the device, the numeral 1 designates the body of a punch press having a base 2 positioned upon the floor 3 and having a work supporting table 4 upon which the work is positioned to be operated upon by a metal punch reciprocable in the head 5 by the usual mechanism employed for such purposes. The tool is caused to descend upon the work positioned upon the table 4 whenever the control rod 6 is moved downwardly under the swinging action of a lever 7, fulcrumed as at 8 upon the frame of the press. Ordinarily, this lever 7 is operated by means of a treadle or hand lever having its fulcrum fixedly mounted in the base of the press, and spring means are associated with the clutch or brake device for returning the lever 7 to an upper normal position; but in view of such mechanism not being illustrated in the present drawing, a tension spring 9 connected to the lever 7 and the side of the press has been illustrated as a substitute for the usual spring return. In many cases, such presses are called upon to operate upon products having such dimensions as to prevent the operator from reaching the usual controls at the base of the machine without using some form of makeshift arrangement which is a hazard to the safety of workmen. The necessity for a remote control of such instrumentalities arose in the production of automobile frames in which one workman handles a frame coming through the production line on an overhead conveyor and because of the required handling, is compelled to stand at the side of the automobile frame opposite that which is disposed upon the table 4 for an operation. In this position, the workman could not reach the usual press control without the makeshifts hereinbefore alluded to. While a specific type of machine to be controlled has been illustrated, for complete appreciation of the device, it is to be understood that its application is not limited thereto as its use will be found advantageous in many other fields and with various other types of machines not only for reaching around the particular work to be operated upon but for concentration of controls of various machines whereby one workman may control several machines from one point of operation.

This remote control device includes a relatively heavy portable base which possesses sufficient weight to be thoroughly stable in any place it is positioned for operation and cannot be kicked around or upset without intentional effort. This base is generally designated by the

5 numeral 10 and is substantially rectangular in configuration, having openings 11 for the passage of extraneous material which may be carried into the device upon the shoes of the workmen. The rear end 12 of the base is provided with a downwardly and inwardly inclined surface 13 for support of the operator's heel when inserted into the same for actuation of the device. The forward end of the base casting is 10 provided with an integral heavy vertical enlargement or toe portion 14 having a forwardly and downwardly inclined surface 15 terminating in a point in close proximity to the floor. At the upper end of this inclined surface is a 15 right angularly projecting shoulder 16 having a notch 17 at the center thereof for registration with a groove 18 extending through the height of the inclined surface 15. This groove is adapted for the reception of a ferrule or sleeve 19 20 clamped upon one end of an armored flexible conduit 20. The upper end of this ferrule is reduced as at 21 and a felt packing washer 22 is disposed in the ferrule 19 between the shoulder formed by the reduced end 21 and the end 25 of the armored cable 20 clamped in the ferrule to prevent the leakage of lubricant disposed in the conduit. A flexible wire cable 23 extends through the reduced nipple 21, packing 22 and all the way through the armored conduit 20. 30 In order to facilitate slidability of the cable in the conduit, the latter is filled with a lubricant as is customary in flexible cable and conduit construction employed for the actuation of mechanical brakes of automotive vehicles. This 35 conduit 21 consists broadly of an inner metallic housing formed by spirally winding wire in compression and an outer coating of textile material woven about the metallic conduit and rendered leak-proof by the application of suitable paints and lacquers under heat treatment. This makes 40 the incompressible and non-extensible flexible conduit fairly heavy to prevent it from "snaking" up on the floor and tripping workmen as they pass over the same. 45 This ferrule constitutes one end of the flexible conduit and is clamped in its groove 18 by means of a metallic bridge bar 24 secured to the inclined surface 15 and against the shoulder 16 by means of suitable fastenings 25. This arrangement, it will be noted, causes the end of the 50 flexible conduit to be inclined downwardly to meet the floor only a short distance beyond the forward end of the base so as to preclude the possibility of workmen tripping over this slightly inclined portion of the conduit. Moreover, this 55 inclination is inducive to retaining the lubricant therein and preventing its leakage through the ferrule into the base 10. The end of the cable 23 projecting inwardly of 60 the toe portion 14 is swivelly connected to a yoke 25 which is pivotally connected as at 26 to the short upwardly extending arm 27 of a bell crank shaped foot treadle fulcrumed as at 29. The other arm 30, of this bell crank is enlarged laterally at its free end and provided with a roughened surface to form a foot treadle portion 31. 65 The base 10 is provided along its two longitudinal margins with vertically extending side walls or flanges 32 which extend from the heel portions 12 to the toe portions 14 and are integral therewith. Each of these side walls or flanges at their forward ends are provided with vertical extensions 34 to form substantially V-shaped seats for an inverted V-shaped shield 70 plate 35 secured to the upper inclined edges of 75

the flanges by means of the fastenings 36. This configuration of the flanges permits ample clearance of the short arm 27 of the bell crank when the foot treadle is depressed to operate the machine. The fulcrum 29 of the foot treadle is provided by a pin 37 extended through the two flanges 32 and prevented from displacement by cotter pins extending through the ends of the pin as illustrated.

5 It is to be noted that the foot treadle in its 10 normal inoperative position as shown in Fig. 3 does not extend above the side flanges 32 and consequently the possibility of accidental operation of the foot treadle is reduced to a minimum. Moreover, the treadle cannot be operated by 15 placing the operator's foot to bridge the two flanges 32 but the foot must be placed in substantial longitudinal alignment with the base in order to engage and depress the treadle. Accidents from accidental manipulation of the device are therefore reduced to a minimum.

10 Referring to Fig. 1, it will be noted that the conduit 20 is of considerable length and it has been found convenient to form the same into lengths of 10 or more feet so as to increase the 20 range of adjustment of the foot treadle with reference to the instrumentality operated thereby. The end 38 of the conduit remote from the foot treadle is fixedly attached to the instrumentality to be operated by means of the clamping plate 30 39 in a position to lead the opposite end of cable 23 to the controlling mechanism of the instrumentality. The free end of the cable is provided with a swivel yoke 40 which is pivotally connected as at 41 to the lever 7. With 35 this arrangement, it will be obvious that upon depression of the treadle 31, the cable 23 will be drawn through the conduit to swing the lever 7 against the tension of the spring 9 to thereby 40 actuate the control rod 6 of the press and cause 45 the tool thereof to descend upon the work. Immediately upon release of pressure of the foot treadle, the spring 9 swings the lever 7 upwardly and thereby draws the cable 23 through the conduit to restore the treadle to the normal position shown in Fig. 3 ready for the next operation. Due to the construction and length of the conduit and cable, it possesses considerable 50 weight and resistance against snaking on the floor, this action being further precluded by rigidly clamping the two ends of the conduit to fixed objects. Consequently, the conduit will lie flat against the floor in whatever position the treadle base is mounted. Due to the flexibility 55 of the cable and conduit, it will be apparent that the treadle base may be shifted to any position remote from the instrumentality controlled and when so located, due to its weight will be entirely stable and not subject to being kicked over or accidentally moved. However, the weight of the 60 base portion is not sufficient to preclude its easy portability to other locations to adapt the control to other kinds of work. It will be obvious that the foot treadle base may be constructed from sheet metal if desired, without sacrificing any 65 of the advantages of the invention.

It is to be understood that various changes in the size, shape and arrangement of parts may be resorted to without departing from the spirit of the invention or the scope of the appended 70 claims.

I claim:

1. Operating means comprising a base adapted to be positioned upon the floor and having a downwardly inclined portion in close proximity 75

to the floor, said inclined portion having a groove therein inclined in the same direction as said surface, a treadle mounted upon said base, a conduit secured within the groove of the inclined surface so as to be directed down into engagement with the floor in close proximity to the base, and a flexible cable extending through said conduit and connected to said treadle.

2. Portable operating means comprising a mobile base, a bell crank treadle mounted therein on a horizontal axis, guard flanges extending vertically from the base on opposite sides of the treadle and having portions extending above the upwardly extending arm of the treadle, the flanges at one end being spaced apart for the introduction of the foot to engage the treadle, said base having an upwardly inclined seat extending toward the free end of the upwardly extending arm of the treadle, a conduit secured in said upwardly inclined seat, and a flexible cable slidably mounted in the conduit and connected to said upwardly extending arm of the bell crank.

3. Portable operating means comprising a mobile base, a bell crank treadle mounted therein

on a horizontal axis, guard flanges extending vertically from the base on opposite sides of the treadle and having portions extending above the upwardly extending arm of the treadle, a hood secured to said upwardly extending portions of the side walls and overhanging the upwardly extending arm of the treadle, the flanges at one end being spaced apart for the introduction of the foot to engage the treadle, said base having an upwardly inclined seat extending toward the free end of the upwardly extending arm of the treadle, a conduit secured in said upwardly inclined seat, and a flexible cable slidably mounted in the conduit and connected to said upwardly extending arm of the bell crank.

4. Portable operating means comprising a mobile base having a cavity therein and a heavy toe piece provided with a downwardly inclined surface, a foot pedal mounted within the cavity, a flexible conduit secured to said inclined surface and led downwardly into engagement with the floor closely adjacent the toe portion of the base, and a flexible cable slidably mounted in the conduit and connected to the foot treadle.
